UNITED STATES PATENT OFFICE.

JACOB SCHWARTZ, OF NEW YORK, N. Y.

TENSION ADJUSTER FOR VIOLIN STRINGS.

Application filed December 20, 1920. Serial No. 431,846.

To all whom it may concern:

Be it known that I, JACOB SCHWARTZ, a citizen of the United States, residing at New York city, in the county of New York and 5 State of New York, have invented certain new and useful Improvements in Tension Adjusters for Violin Strings, of which the following is a specification.

My invention relates to an improved 10 string-holder for the strings of musical instruments, and has reference to that type of holder by means of which the string may be very finely adjusted as to tension and securely held in such adjusted position.

15 The device is especially, although not necessarily solely, useful for the E-string of violins. The latter are wire strings and fine tension adjustment thereof has proven, in practice, to be much more difficult by means 20 of the ordinary wooden peg than to tension the other violin-strings which are of gut.

String-holders of the character contemplated by my invention comprise a supporting member attachable to the tail piece of 25 the musical instrument, and a string-holder proper movably mounted in the supporting member and capable of being set at any desired angle of inclination, and held in position, so as to impart the requisite tension to 30 the string of which one end is secured to the holder. This general type of string-holder is old in the art, and my invention is concerned with improving certain features thereof, as more fully hereinafter pointed 35 out.

One object of my invention is to facilitate the manufacture of such string-holders, and I accomplish this object by eliminating the pivot pin which has been heretofore employed for connecting the holder to its support, and in lieu thereof I provide the support with an enlarged opening through which the holder is passed and then swage the support at the opening so that the holder 45 is secured in position but is capable of rocking to permit of the inclined adjustment thereof.

Another object of the invention is to simplify the operation of placing a string 50 on and removing it from the holder, and to effectuate this object I bifurcate the upper hooked end of the holder arm so that the string may be readily passed through this bifurcated end, and then wrapped about the 55 post and about itself to obtain secure anchorage of the string end.

A third object of the invention is to prevent binding of the holder arm and permit of its being rocked in a constant vertical plane to avoid side distortion of the string, 60 and to this end I provide the outer end of the lower arm of the holder with a depression with which the adjusting screw contacts in effecting adjustment of the holder arm. 65

The invention is illustratively exemplified in the accompanying drawing wherein Fig. 1 is a side elevational view of the device as applied to a violin tail-piece, the latter being shown in section; Fig. 2 is a similar view 70 with certain parts of the improved device in section; Fig. 3 is a horizontal sectional view on the line 3—3 of Fig. 1; Fig. 4 is a view partly in section looking in the direction of the arrows 4—4 of Fig. 1; and Fig. 5 is a 75 top plan view of the support before it has been swaged.

Referring to the drawing, 10 denotes a violin tail-piece suitably apertured to receive a centrally bored or substantially tubular nut 11 which is both internally and externally threaded. The head 12 of the nut is preferably knurled to facilitate manipulation thereof. Passing through the bore of the nut 11 is an adjusting screw 13 having 80 a milled or knurled head 14. The lower end of the nut 11 is designed to engage a threaded opening at the rear of the supporting member or plate 15, the forward portion of such plate projecting somewhat 85 beyond the forward edge of the tail-piece 10. It will be apparent that the plate 15 may be clamped to the tail-piece by screwing the nut 11 down until the head 12 thereof engages the upper face of the tail-piece. 95

The string-holder comprises a string-holding arm 16 and an adjusting arm 17, the two arms being preferably integral and substantially at right angles to each other. The upper end of the arm 16 is bifurcated 100 at 18 to permit the string 19 to be passed therethrough, and adjacent the bifurcation the inner face of the arm 16 is incurved or grooved as at 20 to provide a depressed seat or place of purchase for the retained end of 105 the string 19.

The rear end 17a of the arm 17 is wider than the body portion of the arm, and its upper face is depressed or cupped as at 21 to provide a parabolic surface against which 110 the lower end of the adjusting screw 11 may act. By the arrangement just described, the

adjusting arm as a whole will always be righted by the action of the screw against the curved surface of the depression 21 so that the arm 16 will always stand in the 5 same vertical plane of adjustment.

Near the forward end of the plate 15 is an opening in which the string-holder 16-17 is rockingly supported. The shape of this opening in the partially completed article 10 as shown in Fig. 5 differs from that of the completed device as shown in Fig. 3. In Fig. 5 the opening which is designated 22 is substantially annular and the end of the arm containing the opening is round. However, 15 after the arm has been swaged, i. e., compressed or subjected to a sharp blow, the opening 22^a assumes an elongated, substantially elliptical shape, and the walls thereof engage in oppositely disposed undercut 20 slots 23 in the latter walls of the arm 16 adjacent its junction with the arm 17. Each slot 23 has its walls somewhat flared or divergent as shown in Fig. 2, and with this 25 construction the holder 16-17 is confined in the support 15 without the use of a pivot pin, but capable of rocking therein. When a pivot pin is employed, the arm 16 as well as the walls of the support 15 adjacent the opening 22 must be pierced, and in assembling the device, these holes must be accurately alined to receive the pin. This work 30 is time consuming and expensive, and is entirely dispensed with by constructing the device in the manner above described, in accordance with my invention.

The operation of my invention is very simple, and may be briefly described as follows:—With the parts assembled as shown in Figs. 1 and 2, the loose end of the string 40 19 is passed down through the bifurcation 18 and then wrapped one or more times about the arm 16 at the grooved portion 20, and the string may also be wound upon 45 itself as shown at 19^a. Thereupon the screw 13 is turned up or down thus rocking the arm 16 to more or less tension the string

19 until the desired tautness is obtained. Very fine adjustment is made possible by the screw threaded engagement between the screw 13 and the inner screw threaded face 50 of the nut 11, and when such adjustment is completed the screw is released and the adjustment remains without the use of any other locking arrangement for the parts.

I claim:—

1. A string holder of the character described, comprising a supporting plate having an opening at one end thereof, an adjusting member carried at the opposite end of said plate, and a holder arm passing through 60 and held in said opening and having one of its ends bifurcated to receive a string and the other of its ends being provided with a depression adapted to receive the end of said adjusting member.

2. A string holder of the character described, comprising a supporting plate having an opening at one end thereof, an adjusting member carried by the opposite end of said plate, and a holder arm held in said opening, said holder arm having one end bifurcated and its inner face incurved adjacent said bifurcation and the other free end thereof being provided with a depressed curved portion adapted to receive the end 75 of said adjusting member to adjust the inclination of the string holder.

3. In a string tensioning device, the combination with a supporting bed plate having an opening at one end thereof of an L-shaped 80 string holder loosely fulcrumed in said opening, said holder being provided with an open ended slot at one end thereof to receive a string and a curved depression adjacent its opposite end, and an adjusting member carried by said plate and having one end designed to cooperate with said depression to adjust the inclination of said string holder 85 in a vertical plane.

In testimony whereof I have affixed my 90 signature.

JACOB SCHWARTZ
